UNITED STATES PATENT OFFICE.

THOMAS LEE, OF CINCINNATI, OHIO.

IMPROVEMENT IN RAIN-WATER CUT-OFFS.

Specification forming part of Letters Patent No. 125,742, dated April 16, 1872.

I, THOMAS LEE, of Cincinnati, in the county of Hamilton and State of Ohio, have invented a Rain-Water Cut-Off, of which the following is a specification:

Nature and Objects of the Invention.

My invention relates to a peculiarly-formed hinged and sliding spout for rain-water pipes of buildings, whereby the rain may be conducted into the cistern, or may be directed therefrom at will, so as to avoid soiling the contents of the cistern with the comparatively dirty washings of the roof at the commencement of a shower.

General Description with Reference to the Drawing.

Figure 1 is a perspective view of a rain-water spout provided with my improvement set for discharging the water. Fig. 2 is a vertical section of the same. Fig. 3 is a vertical section of the same parts set for conducting the water into the cistern.

A pipe, A, leading from the house-gutter, conducts into a box or chamber, B, from whose lower end a spout, C, leads, by shiftable elbow or other duct, H, into the cistern-pipe, or one of several such pipes, D D'. On the front of the box B is an opening, b, and hinged to said

box, at or near the lower edges of said opening, is a spout, E whose outer edge, being depressed, as in Figs. 1 and 2, operates to discharge the effluences of the roof, or, being elevated and closed against the box, as in Fig. 3, operates to conduct them into the cistern. In order more effectually to accomplish this purpose, the rear or inner edge of said hinged spout has an upturned lip, e, and is connected by pivot F to a sliding section, G, which, in the open condition of the spout E, leads from pipe A into said spout, as in Figs. 1 and 2, and in the closed condition of said spout conducts the water directly down into the cistern-spout, as in Fig. 3.

Claim.

I claim as new and of my invention—

The spout E, hinged at its center to the box B, and provided with a lip, e, in combination with the sliding tube G pivoted to the spout E and pipes A. C, all constructed, arranged, and operated as set forth.

In testimony of which invention I hereunto set my hand.

THOMAS LEE.
